UNITED STATES PATENT OFFICE.

OTTO FERDINAND MAYER, OF BERLIN, GERMANY.

CASH-REGISTER.

SPECIFICATION forming part of Letters Patent No. 723,475, dated March 24, 1903.

Application filed March 3, 1902. Serial No. 96,540. (No model.)

To all whom it may concern:

Be it known that I, OTTO FERDINAND MAYER, engineer, a subject of the King of Prussia, German Emperor, and a resident 5 of 4 Charlottenstrasse, Berlin, Kingdom of Prussia, German Empire, have invented certain new and useful Improvements in Cash-Registers, of which the following is an exact specification.

16 My invention relates to improvements in cash-registers, and has especially for its purpose to provide an arrangement for stopping the movement of the key-levers and indicating-wheels at the desired points.

15 My invention is represented in the accompanying drawings, in which—

Figures 1 and 2 are diagrams of the key-lever arrangement in different positions. Fig. 3 is a vertical section through part of a 20 cash-register, showing my new arrangements.

In the accompanying drawings, *a* represents the keys arranged upon the keyboard *c*. The key-shafts *a'* of the keys *a* are guided in the keyboard *c* and in the guide-plate *d*, 25 arranged underneath the keyboard *c*. In the shafts *a'* of the keys *a* pins *e* are provided, which have the purpose of preventing the possibility of drawing the keys perfectly out of the keyboard. The keys *a* are pressed up-

30 ward by means of spiral springs *b*, fixed to the shafts *a'* on the one side and on the other side to the keyboard *c*, whereby it is attained that the pins *e* are always situated directly underneath the keyboard *c*. Underneath the 35 pins *e* a double-armed lever *f*, fulcrumed at *g*, is situated, so that by pressing the keys *a* downward the longer arm of the lever *f*, which arm is situated underneath the pins *e*, is pressed downward. The shorter arm of

40 the lever *f* is connected, by means of the connecting-rod *h*, to the shorter arm of a lever *i*, fulcrumed at *j*. Now it will be clear that in case the longer arm of the lever *f* is pressed downward the longer arm of the lever *i* will 45 be raised until it pushes against the pin *e* of that key by the depression of which the longer arm of the lever *f* was pressed downward. It is herewith attained that the downward movement of the lever *f* is stopped in

50 the moment in which the lever *i* pushes against the pin *e* of the respective key. If now the longer arm of the lever *f* is pressed

down by means of the key situated nearest to the fulcrum *g*, the lever will swing around a larger angle than it will swing in case it is 55 pressed downward by means of a key situated in a greater distance from the fulcrum *g*—that is to say, it will swing around a larger angle before the longer arm of the lever *i* pushes against the respective pin *e* and here- 60 with stops the swinging of the lever *f*. The swinging of the lever *f* is now transferred to the indicating-wheel *k*, so that the more the lever *f* will swing—that is to say, the nearer the key *a*, by means of which the swinging of 65 the lever *f* is effected, is situated toward the fulcrum *j*—the more the wheel *k* will turn.

The connection between the lever *f* and the wheel *k* may be effected by means of a string, as indicated in Figs. 1 and 2, or a third 70 one-armed lever *l* may be provided, as shown in Fig. 3, which lever is moved by means of a pin *m*, fixed to a nose of the lever *f*, and to the free end of which lever a string *n* is fixed, which passes around the pulley *o*, fixed upon 75 the shaft *p*, upon which the indicating-wheel *k* is also fixed. The string *n* is connected to a spiral spring *q*, which always tends to bring the three levers *l*, *i*, and *f* into their normal position. (Shown in Fig. 3 of the drawings.) 80

On the outer circumference of the wheel *k* numbers are printed, and the whole mechanism is adjusted so that in case one of the keys *a*, which are also provided with numbers, is pressed downward the wheel *k* turns 85 until the number corresponding to the number of the respective key is situated behind the cut-out *r*, provided in the casing *s* of the apparatus.

In order to avoid inaccuracies which might 90 arrive by the wheel *k* in consequence of the *vis viva* swinging too far, a ratchet-wheel *t* with spiral-formed circumference is provided. At the side of this ratchet-wheel one arm of a double-armed lever *u*, fulcrumed at *v*, is 95 situated, to which arm a pin *w* is fixed, which engages with the teeth of the ratchet-wheel *t*. Now the other arm of this double-armed lever *o* is situated underneath a nose *f'* of the lever *f*, so that the situation of the pin *w* depends 100 upon the situation of the lever *f*. If the wheel *k* is turned (by pressing down one of the keys *a*) in the direction of the arrows shown in the drawings, the pin *w*, fixed to the

lever u on account of the nose f' being raised and taking the lower arm of the lever u , which is connected with the nose f' by means of the spiral spring u' , along, will move toward the axle p . As soon as the swinging of the lever f stops the pin w is situated at the spot corresponding to the situation of the lever f —that is to say, the pin w is situated in the same distance from the axle p in which 10 that tooth of the ratchet-wheel t which in this moment should engage with the pin b is situated from the shaft p . In case now the wheel k turns too far on account of the 15 *vis viva* of the same it will return immediately by the action of the spiral spring q until the respective tooth of the ratchet-wheel t engages with the pin w , the position of which corresponds to the position of the lever f .

In order to hold the key a which has been 20 pressed downward in its position, pins x are provided on the lower ends of the key-shafts a' , and the connecting-rod h is provided with noses y , which in case the key a has been 25 pressed down and the connecting-rod h has consequently moved to the left-hand side engage with the pins x of the key-shaft and herewith hold the keys in their depressed position, herewith holding also the indicating-wheel in its position. In order to release 30 the indicating-wheel and the key, the pin w must be disengaged of the ratchet-wheel t , so that the lever mechanism returns to its normal position by the action of the spiral spring q , hereby bringing also the connecting-rod h back to its normal position and releasing 35 the respective nose y from the respective pin x , so that the key will return to its normal position by the action of the spiral spring b of the same.

40 In the construction shown in the drawings in Fig. 3 the upper sides of the levers f and i are curved, which has the purpose of attaining that all the keys must be pressed down for the same distance until their movement 45 is stopped; but it will be understood that these upper sides may also be straight, as is shown in the diagrams shown in Figs. 1 and 2 of the drawings.

Having thus fully described the nature of 50 my said invention, what I desire to secure by Letters Patent of the United States is—

55 1. In a cash-register, the combination of a two-armed key-lever, a series of normally elevated spring-actuated keys provided with pins projecting above the longer arm of the key-lever, with a second two-armed lever, the longer arm of which is situated at the side of the longer arm of the key-lever, and the fulcrum of which is situated opposite to the fulcrum of the key-lever, a connecting-rod connecting the shorter arms of both levers, an indicating mechanism and means for transferring the movement of the levers to the indicating mechanism, substantially as described and for the purpose set forth.

60 2. In a cash-register, the combination of a two-armed key-lever, a series of normally ele-

vated, spring-actuated keys provided with pins projecting above the longer arm of the key-lever, with a second two-armed lever, the longer arm of which is situated at the side of the longer arm of the key-lever, and the fulcrum of which is situated opposite to the fulcrum of the key-lever, a connecting-rod connecting the shorter arms of both levers, an indicating-wheel and a string for transferring the movement of the levers to this indicating-wheel, substantially as described and for the purpose set forth. 70

75 3. In a cash-register, the combination of a two-armed key-lever, a series of normally elevated spring-actuated keys provided with pins projecting above the longer arm of the key-lever, with a second two-armed lever, the longer arm of which is situated at the side of the longer arm of the key-lever, and the fulcrum of which is situated opposite to the fulcrum of the key-lever, a connecting-rod connecting the shorter arms of both levers, an indicating-wheel, a string for transferring the movement of the levers to this indicating-wheel, a two-armed lever moved by a nose fixed to the key-lever and provided with a pin, and a spiral-formed ratchet-wheel, the teeth of which engage with the pin of this lever, substantially as described and for the purpose set forth. 85

90 4. In a cash-register, the combination of a two-armed key-lever, a series of normally elevated spring-actuated keys provided with pins projecting above the longer arm of the key-lever, with a second two-armed lever, the longer arm of which is situated at the side of the longer arm of the key-lever, and the fulcrum of which is situated opposite to the fulcrum of the key-lever, a connecting-rod connecting the shorter arms of both levers, an indicating-wheel, a string for transferring the movement of the levers to this indicating-wheel, a two-armed lever moved by a nose fixed to the key-lever and provided with a pin, a spiral-formed ratchet-wheel, the teeth of which engage with the pin of this lever, pins provided at the lower ends of the key-shafts, and noses fixed to the connecting-rod 100 connecting the shorter arms of the levers first mentioned, said noses being adapted to engage with the pins at the lower ends of the key-shafts as soon as the levers begin to move, substantially as described and for the purpose set forth. 105

110 5. In a cash-register, the combination of a two-armed key-lever, a series of normally elevated spring-actuated keys provided with pins projecting above the longer arm of the key-lever, with a second two-armed lever, the longer arm of which is situated at the side of the longer arm of the key-lever, and the fulcrum of which is situated opposite to the fulcrum of the key-lever, a connecting-rod connecting the shorter arms of both levers, an indicating-wheel, a one-armed lever situated at the side of the key-lever so as to be moved by a pin fixed to the same, a string for trans- 115

ferring the movement of this lever to the indicating-wheel, a two-armed lever moved by a nose fixed to the key-lever, and provided with a pin, a spiral-formed ratchet-wheel, the 5 teeth of which engage with the pin of this lever, pins provided at the lower ends of the key-shafts, and noses fixed to the connecting-rod connecting the shorter arms of the levers first mentioned, said noses being adapted 10 to engage with the pins at the lower ends of

the key-shafts if the keys are in their depressed position, substantially as and for the purpose set forth.

In testimony whereof I have signed my name to this specification in the presence of 15 two subscribing witnesses.

OTTO FERDINAND MAYER.
